UNITED STATES PATENT OFFICE.

JOHN FREDERICK BURCH AND ARNOLD HARRISON MORTON, OF BILLINGS, MONTANA.

SAFETY RAILWAY GATE.

Application filed March 26, 1927. Serial No. 178,671.

The present invention relates to improvements in safety railway gates and has for an object to provide a gate structure and operating mechanism for the crossings of railroads, whereby both a visual and audible signal will be given to motorists and pedestrians in a more substantial attempt to avoid disasters at grade crossings.

It is another object of the invention to provide an automatically operating gate and signal apparatus in which the movement of the device to the operative or danger position will be controlled by the advance of a train; and in which the mechanical parts of the device will be grouped into small compass for easy and faithful operation and for economy in the manufacture and installation of the apparatus.

A further object of the invention resides in providing an automatic gate and signal device for railway crossings which will dispense with the necessity for gatemen and eliminate the human element in the operation of the device, making the actuation of the signals most positive.

With the foregoing and other objects in view, which will readily become apparent to those skilled in this art, the invention will be described the more specifically hereinafter in connection with the accompanying drawings, in which like symbols refer to like parts throughout the several views, and in which—

Figure 1 is a front elevation of a safety railway gate apparatus constructed in accordance with our present invention;

Figure 2 is a vertical section taken through the apparatus on an enlarged scale with portions of the gates broken away;

Figure 3 is also a vertical section taken at substantially right angles to Figure 2;

Figure 4 is a horizontal section taken on the line 4—4 in Figure 2;

Figure 5 is a fragmentary side view of one of the gates, with a portion of the stop light casing broken away;

Figure 6 is a transverse section taken on the line 6—6 in Figure 5;

Figure 7 is a top plan view of the apparatus in the operative position; and,

Figure 8 is a diagrammatic view of the preferred form of circuit arrangement.

Referring more particularly to the drawings, the apparatus consists generally of one or more gates, two such gates 9 and 10 be-

ing shown in the embodiment of the apparatus illustrated; such gates as shown in Figure 1 being normally held in an up-raised initial position and adapted to be swung down to the substantially horizontal position indicated in dotted lines for indicating by the outstretched condition thereof the approach of a train toward the crossing. It will be noted that these arms in no sense constitute a barrier to the crossing, but on the contrary they are suspended by an appropriate pedestal at an indicating position which is well above the tops of vehicles, an automobile being indicated in Figure 1 to show generally the relation between the vehicle and the signal apparatus. The vehicle can pass freely beneath the signal apparatus without damage either to the gate or to the vehicle; yet the gate is clearly visible to the driver of the vehicle and constitutes a visual warning that cannot be overlooked, or ignored.

In addition, each gate preferably carries a number of pendant preferably flexible devices 11, which are pivotally hung from the arms as indicated at 12 and are of a length to extend down in front of portions of the vehicle to be struck by the vehicle in passing beneath the gate, whereby in a more effective manner to bring to the attention of the driver of the vehicle the danger condition of the gate apparatus. These pendants will be constructed of such flexible material as to avoid injury to the vehicle or the finish thereof.

The gates are pivoted at or near their lower ends as indicated at 13 and 14 to laterally extending lugs 15 and 16 on a casing or housing 17, which is mounted at the upper portion of the pedestal 18. This casing is arranged to confine the working parts of the device and is provided in the side walls thereof adjacent the lugs 15 and 16 with slots 19 and 20. Through these slots project the right angularly turned terminal ends 21 and 22 of the gates 9 and 10. These terminal ends are slotted or forked as indicated at 23 and provided with the pivot pins 24 and 25 with which the outer ends of the links 26 and 27 are connected. These links extend inwardly and into slots 28 made in opposite sides of a travelling nut or block 29. Pivot pins 30 and 31 extend through the slotted side portions of the nut 29 and through the inner end portions of the links 26 and 27.

The nut or block 29 is internally threaded

and mounted for movement along the threaded shaft 32, which is shown as mounted substantially vertically in the casing 17, having its upper reduced end 33 received in a bearing collar 34, affixed to the top of the casing while its lower reduced end 35 is arranged to rest upon a bearing block 36, held in a bearing box 37 extending downwardly from the bottom of the casing 17 and having the retaining flange 38 by which the bearing 36 is held in place. Any other bearing means might be employed, it being understood that the shaft is capable of a rotary, but not of an axially sliding motion, whereby when rotation is imparted to such shaft, the nut 29 will be caused to traverse the shaft longitudinally in accordance with the direction of rotation thereof. The movement may be derived from any appropriate source, for instance, from the electric motor 39 shown as mounted in the casing 17 and having on its armature shaft the beveled pinion 40 disposed in mesh with the complementary beveled pinion 41 affixed to the threaded shaft 32 near its lower end. The motor 39 will be of the reversible type in order to shift the travelling nut up and down the shaft 32, as becomes necessary in the raising and lowering of the signal gates. The gearing 40, 41, shown may or may not be used; in many cases, a reduction gear will be required.

The travelling nut 29 as shown in Figures 3 and 4 is provided upon its rear face with a travelling contact finger 42 arranged to move in a groove 43 of a fixed contact pillar composed of three sections—namely, a lowermost section 44 of insulating material or of conducting material insulated and cut off from the source of current, an intermediate section 45 insulated as indicated at 46 and 47 from the adjoining sections, and an upper longer contact section 48 insulated from the intermediate section 45. In its upward movement the travelling contact finger 42 is adapted to successively wipe over the three sections 44, 45 and 48 in the order named.

On the top of the casing 17 may be placed the usual cross arm indicating device 49, which indicates the railroad crossing and in practice these words will be written on the cross arms.

Immediately below the casing 17 is a lamp housing 50, having lenses 51 extending on all four sides as illustrated. Within the lamp housing are two electric lamps, a yellow lamp 52 and a red lamp 53. These lamps may be mounted in any appropriate way and the circuit wires therefor are led in through the hollow pedestal 18, which pedestal is a convenient support for holding the oil lamps 54 which city ordinances usually require on street apparatus. The hollow pedestal 18 may be flanged as indicated at 55 to receive the bolts or other fastenings 56, by which it is connected to the heavy base 57. The base is

also preferably hollow or provided with a passage to admit the wires to the lamps 52 and 53.

As shown in Figures 1 and 3, an electric bell 58 is employed, this bell being mounted at 70 any convenient point on the apparatus. In the present case, we have illustrated it as affixed to the pedestal 18.

The interior of the casing 17 is accessible through a door 59 hinged as indicated at 60 to 75 the front wall of such casing. This door and the opposite exterior wall of the casing will form excellent backgrounds to bear such inscriptions as "Safety first" and the entire pedestal may be painted in the black and white so striped arrangement which has now been commonly adopted as a danger signal in itself.

The gates are constructed of metal or other approximate material of the desired length 85 and shape but they preferably include at substantially a midway point stop light casings, such for instance, as shown in Figures 5 and 6, in which the metallic casing is indicated generally at 61, and the red bulb therein at 90 62. The glass panels are represented at 63 and show at both sides of the gate. These panels preferably bear the word "Stop". Either the lamp or the panel may be tinted red. 95

In Figure 8 we have shown a circuit diagram in which 64 represents a battery or other source of current coupled to the reversible motor 39 by the wires 65 and 66. The circuit includes an automatic reversible 100 switch 67 and the ground wire 66 is connected to one rail 68 while the other side of the circuit 65 is coupled to the insulated rail section 69, so that when the train is on this section, the motor 39 will be energized. 105

In Figure 8 is also shown a battery or other source of current 70 for operating the lighting and bell circuit. The yellow lamp 52 in the lamp housing 50 and the bell 58 are preferably connected in multiple in a circuit 71, 110 72, which includes the intermediate contact section 45, the contact finger 42, travelling nut 29 and screw shaft 32.

The red lamp 53 and the lamp housing 50 and the red stop lamp 62 in the gates are also 115 preferably connected in parallel in a circuit 73, 74 which includes also the uppermost contact section 48, the movable contact finger 42, travelling nut 29, screw shaft 32, return wire 72 and the battery 70. 120

In operation, the initial inactive position of the parts is as shown in full lines in Figure 1, in which condition both the motor and the light circuits are open and no lights are burning, save the oil lamps 54. As a train approaches the crossing, it will close the circuit 65, 66 through the electric motor 39, thereby rotating the screw shaft 32 and elevating the travelling nut 29. This nut, due to its connection through the links 26 and 27 with 125 130

the gate arms, will proceed to lower the latter. At the same time the contact finger 42 is elevated. When this contact finger passes off the lower contact section 44 and the insulation 5 46 above it and begins to wipe across the intermediate contact section 45, it closes the circuit through the bell 58 and yellow lamp 52 in the lamp housing 50. This yellow lamp shows from four sides of the housing 50 through 10 the four lenses 51, which are placed at right angles to one another. The light can thus be seen in the roadway from both directions and it is also visible by the engineer of the approaching train, so as to apprise him of the 15 fact that the apparatus is in working order.

As the travelling nut 29 and its contact finger 42 continue to rise, the contact finger passes off the intermediate contact section 45 and on to the uppermost contact section 48 20 whereupon the circuit to the bell 58 and the yellow light 52 is interrupted and the circuit through the red lamp 53 in the housing 50 and the red lamps 62 in the gates is closed. We have thus established an initial period in 25 which the yellow lamp is lighted and the bell rung to both visibly and audibly notify those approaching the crossing of the near presence of the train. We have further established a final condition in which the caution yellow 30 lamp gives place to the red danger signal and in this latter condition the gates reach their lowermost position in which the pendant devices 11 are stretched across the roadway and in addition the red lamps 62 are illuminated 35 behind the stop panels.

The gates 9 and 10 may be lowered and elevated either slowly or rapidly and this result may be obtained by changing the pitch 40 of the threaded shaft 32 and nut 29, or the same result may be accomplished by a change 45 in the ratio of the gearing 40, 41.

After the train has passed the crossing, the motor 39 will be reversed by means of any appropriate well-known mechanism, as for 45 instance, the automatic reversing switch 67 and relay construction. The arms are thus elevated to the position shown in full lines in Figure 1 and the light circuits interrupted, thus placing the device in condition for the 50 next actuation.

When the gates descend to the lowermost position the automatic apparatus 67 will open the motor circuit and the motor will thus cease to run, economizing on the further use of current. Of course, the motor circuit could be 55

closed manually as by the use of button switches or the like, and this would be particularly desirable at busy crossings where great numbers of tracks are involved. Through this arrangement also one gateman 60 is enabled to control the gates for a number of successive crossings. The device is placed in the center of the roadway to either or both sides of the tracks, or if desired, between the tracks where sufficient spacing of the 65 tracks permits, as where two main lines are crossing the road at adjacent points. In case a single gate arm is used, the pedestal could be placed at the side of the road, rather than at the middle and from one to four of the 70 pedestals could be placed at each crossing.

It will be obvious that many changes in the construction, combination and arrangement 75 of parts could be made, which could be used without departing from the spirit of my invention, and we do not mean to limit the invention to such details, except as particularly pointed out in the claim.

Having thus described our invention, what we claim and desire to secure by Letters Patent of the United States is:—

In a railway gate signal, a pedestal, a pair of spaced gates pivoted on the pedestal and each having an angle arm at its inner end, a threaded shaft in the pedestal between and substantially in the plane of said angle arms, means for turning the shaft, a traveler nut on the shaft having a laterally projecting finger, links between the angle arms and the traveler nut for lowering the gates gradually upon the upward travel of the nut on the shaft, a contact pillar in the pedestal in parallel relation to the shaft and having a vertical groove therein for receiving and holding the finger of the traveler nut, said contact pillar having in said groove bottom, intermediate and top fixed contacts insulated from one another and from the pedestal and over which said finger is adapted to traverse, a warning signal circuit including said intermediate contact and the traveler nut to be closed by the latter during the initial lowering of the gates, and a danger signal circuit including said top contact and the nut to be closed by the latter during the final closing 95 of the gates and while the nut remains in contact with the top contact.

JOHN FREDERICK BURCH.
ARNOLD HARRISON MORTON.
